UNITED STATES PATENT OFFICE

2,133,051

METAL ROLLING MILL

Claude A. Bollinger, Gary, Ind.

Application March 24, 1937, Serial No. 132,823

1 Claim. (Cl. 80—31.1)

This invention relates particularly to the joining of metal strips in superimposed relationship by passing them through a set of pressure rolls while providing sufficient heat to effect interwelding, but the broad principles of the invention are applicable to many metal rolling problems. The primary object is to prevent slipping of the strips either relative one another or relative the rolling surfaces necessarily involved.

10 Another object of practically equal importance is to roll the strips together so that they are respectively brought into complete contact with each other.

15 Still other objects may be inferred from the following disclosure.

In the accompanying drawing:

Figure 1 is a sectional elevation of a mill embodying the principles of the present invention.

20 Figure 2 is a partially sectioned view showing the roll elements of this mill.

The mill includes a housing 1 which mounts two parallel rotary mandrels 2 having journals 2^a and fluted ends 2^b. These mandrels 2 are rather similar to metal rolling rolls, the journals 2^a being adapted to turn in suitable bearings with those of the upper mandrel engaged by suitable holdowns 3, and the fluted ends 2^b being adapted for connection with powered spindles.

30 However, these mandrels 2 differ from ordinary rolling rolls in that they have circumferentially grooved surfaces, these grooves being marked 2^c in the drawing, and in that they work through a set of hollow rolls 4 which encircle the mandrels, these rolls being internally grooved to provide grooves 4^a which fit the grooves 2^c of the mandrels. The rolls 4 have inside diameters which are larger than the outside diameters of the mandrels 2, whereby the rolls 4 rotate eccentrically respecting the mandrels 2 when they are pressed together by the operation of the holdowns 3. The diameters of the respective parts should be related so that the rolls 4 may be slid freely over the mandrels 2 when this is necessary, it being obvious that the inside diameter of the rolls must be sufficiently large to permit clearance between the various grooves.

In the embodiment of the invention under discussion, three strips are being welded together. The inside one of these strips may be commercially pure iron, while the outside strips may be copper, nickel or an alloy, or any of the other metals commercially used in the production of multiple-layer strip.

55 Guides 5 lead the iron strip straight through

the pass of the rolls 4 and in a plane with the same, from a furnace 6 (of which only the end is shown), then over a deflector roll 7 and so to a tension reel 8. Suitable means for driving this reel 8 so as to apply proper tension are known to those skilled in the art.

The outside metal strips are fed from coil boxes 9 which are offset relative the pass line of the rolls 4, through friction blocks 10 and from there tangentially onto the surfaces of the rolls 4, the 10 strips wrapping around these rolls through 180 degree arcs and eventually passing between them so as to be brought into contact with the middle strip. It now becomes obvious that the tension reel handles all three strips, the heat from the iron strip being sufficient to effect the welding.

According to the prior art, when the general operation under discussion is to be carried out, the strips to be joined are passed between solid 20 rolling rolls very similar to, if not the same, as metal rolling rolls. Furthermore, all the strips to be joined are fed through the rolling pass in at least approximately the same plane, this plane coinciding with the pass line of the rolls used. 25

The above procedure is beset with two big difficulties, one of these being a decided tendency of the strips to slip relative the working rolls and one another, while the other is the inability of the rolls to bring the strips into perfectly 30 flat, complete contact with each other when they are fed in the same common plane straight through the roll pass. It requires little imagination to realize that both of these difficulties present serious obstacles in the way of obtaining a 35 product wherein the various strips are integrally united in such a manner as to permit subsequent processing, such as cold rolling and the like, or their fabrication into ultimate products, this often involving drawing and forging effects. 40

Such difficulties are largely obviated by the invention under discussion. The rolls 4 rotating eccentrically respecting the powered mandrels 2 provide endless rolling surfaces that are under the same rolling pressure and have much the same 45 motion as the strips, the latter therefore being imparted the same linear speed as the peripheral speed of the rolls. Interposed friction-reducing films, such as are generally encountered in practice, are relatively immaterial. The rolls 4 provide endless successions of continuously overlapping, progressively curved surfaces, as contrasted to the rolling surfaces of ordinary rolls. 50 The contrast may be to some extent compared 55

with that existing between a tractor driven by an endless chain and one driven by wheels.

Furthermore, due to the strips being led tangentially onto the roll surfaces by means offset from the pass line of the rolls, the strips must wrap at least partially around the roll surfaces prior to their being pressed into contact with the center strip. This, in conjunction with the feature of the eccentrically driven rolls 4, assures not only that no slipping will occur but, also, that the outside strips will have conformed exactly to the cylindrical surfaces of the rolls prior to their being pressed onto the center or iron strip. This wrapping feature also provides time for the outermost strips to absorb a large amount of the heat from the rolls 4, it being remembered that the center strip is heated and that heat from this strip is being constantly absorbed by the rolls 4.

Although the principles of the invention have been disclosed by means of a specific example in accordance with the patent statutes, it is not in-

tended that its scope be thereby limited exactly to this example, except to the extent defined by the appended claim.

I claim:

A mill characterized by a set of hollow rolls and mandrels passed through said rolls and provided with holdowns for applying pressure to said rolls, the inside diameters of the latter being materially greater than the outside diameters of said mandrels, said mill being adapted to join strips in superimposed relation and including means for feeding one strip, means for heating said strip and means offset from the pass line of said mandrels for feeding at least one other strip tangentially into contact with one of said rolls so that it wraps therearound to a sufficient extent to abstract substantial amounts of heat from said roll imparted thereto by the first named strip, prior to passing through said rolls with the first named strip.

CLAUDE A. BOLLINGER.
